UNITED STATES PATENT OFFICE.

ROBERT S. WIESENFELD, OF BALTIMORE, MARYLAND.

FISH BAIT OR LURE.

Application filed September 10, 1925. Serial No. 55,481.

To all whom it may concern:

Be it known that I, ROBERT S. WIESENFELD, a citizen of the United States, residing at Baltimore city, State of Maryland, 5 have invented certain new and useful Improvements in Fish Baits or Lures, of which the following is a specification.

This invention relates to fishing lures and has special reference to the type of fish lure 10 known as a spoon hook.

One important object of the invention is to provide a spoon hook having means whereby the fisherman may somewhat vary the shape of the device so as to change the 15 manner in which it acts when drawn through the water.

A second important object of the invention is to provide a spoon hook which will not only revolve in the water but which will 20 also dart from side to side thus combining the effectiveness of the revolving type of spoon hook with the effectiveness of the darting type.

A third object of the invention is to provide 25 an improved arrangement for securing the hook to the spoon so that the distance the former extends behind the latter may be varied at will.

A fourth object of the invention is to provide 30 improved means whereby the hook may be attached to the spoon so that it cannot only be shifted as above but will be rigidly held when so shifted.

With the above and other objects in view 35 as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is an inside or front view of one 45 form of spoon hook constructed in accordance with this invention.

Figure 2 is a longitudinal section there- through.

Figure 3 is an outside or back view of the 50 spoon hook.

Figure 4 is a section on the line 4-4 of Figure 1.

Figure 5 is a section on the line 5-5 of Figure 1.

55 The body of the spoon forming part of this invention consists of a pisciform plate

of thin metal or other suitable material which is transversely flat but which is curved longitudinally. The rear portion 10 is longer than the forward portion 11 but both portions have substantially equal curvature, being connected by an abruptly curved bend 12. Thus the front portion in its general shape is at an angle to the rear portion.

At about the widest portion of this body there is provided on each edge a fin 13 one of which is preferably bent in a direction inwardly of the body while the other is bent in the opposite direction, the two, 70 when thus bent, acting somewhat like propeller blades to cause spinning of the spoon when it is drawn through the water. Nevertheless, the user may, if he wishes bend these fins to conform to the curvature of the 75 body or to project both in the same direction so that variety of movements may be given the spoon.

On the central longitudinal line of the body there is provided, at the forward end, 80 an opening 14 to permit the spoon to be attached, by a link 15 to a swivel 16. In the rear portion of the preferred body there is a groove 17 which is formed by stamping the metal inwardly and this 85 groove has a plurality of circularly enlarged portions 18 each having an opening 19 associated therewith to receive the shank 20 of an eye 21, the eye being secured in selected position by a nut 22. At the tail 90 end of the body a second groove 23, stamped in a direction opposite the first is provided and these grooves receive the shank 24 of the hook, the eye 25 being held by the eye 21 and the bill 26 projecting rearwardly 95 of the spoon. The eye 25 thus fits in the enlarged portions 18 of the groove 17 and, while the hook may be shifted longitudinally it is very securely held.

In the form shown in Figure 6 these 100 grooves are eliminated and only the spaced openings 19 are provided so that the hook may be freely suspended from the spoon at selected points.

There has thus been provided a simple 105 and efficient device of the kind described and for the purpose specified.

It is obvious that minor changes may be made in the form and construction of the invention without departing from the material 110 spirit thereof. It is not, therefore desired to confine the invention to the exact form

herein shown and described, but it is desired to include all such as properly come within the scope claimed.

Having thus described the invention, what is claimed as new, is:

1. In a spoon hook, a spoon consisting of a strip of metal of pisciform outline and having its forward end sharply bent at an angle to its rear end throughout its full width, both of said ends being curved longitudinally and in the same direction throughout and flat transversely, said spoon further having fins on its lateral edges bendable out of conformity with the curvature of the body said fins being positioned rearwardly of the bend.
2. In a spoon hook, a spoon consisting of a strip of metal of pisciform outline and having its forward end sharply bent at an angle to its rear end throughout its full width both of said ends being curved longitudinally and in the same direction throughout, said spoon further having fins on its lateral edges bendable out of conformity with the curvature of the body said fins being positioned rearwardly of the bend.
3. In a spoon hook, a spoon consisting of

a strip of metal of pisciform outline and having its forward end sharply bent at an angle to its rear end, throughout its full width, both of said ends being curved longitudinally and in the same direction throughout and flat transversely, said spoon further having fins on its lateral edges bendable out of conformity with the curvature of the body said fins being positioned rearwardly of the bend.

4. In a spoon hook, a spoon body provided with spaced openings for the selective reception of hook attaching means, and hook attaching means secured in a selected opening, and a hook connected to said attaching means, said body also having grooves aligned with said openings whereby to receive the shank of the hook, one of said grooves having spaced enlargements at each opening to receive a hook eye.

In testimony whereof I affix my signature.

ROBERT S. WIESENFELD.
